UNITED STATES PATENT OFFICE.

THOMAS SHIVERICK AND LEANDER J. WYNN, OF CHICAGO, ILLINOIS.

ROTARY STEAM-ENGINE.

SPECIFICATION forming part of Letters Patent No. 357,863, dated February 15, 1887.

Application filed February 23, 1886. Serial No. 192,829. (No model.)

To all whom it may concern:

Be it known that we, THOMAS SHIVERICK and LEANDER J. WYNN, citizens of the United States, and residents of Chicago, Cook county, State of Illinois, have invented new and useful Improvements in Rotary Steam-Engines, of which the following is a specification, reference being had to the accompanying drawings illustrating the invention, in which—

10 Figure I is a face view of an engine embodying our invention, with one head-plate removed to give a view of the interior construction; Fig. II, a central section taken on line *x*, Fig. I; Fig. III, a face view of the engine with the face-plate and cylinder removed to show the form of the cam-groove; Fig. IV, a transverse section of one of the piston-guides and piston therein on line *y*, Fig. I, both heads being shown.

15 This invention relates to an improvement in rotary steam-engines which may be run in either direction; and the novelty thereof consists in the form of the cam-grooves, which direct the movement of the four pistons to and from the periphery of the case, whereby steam is taken and discharged in the cylinder at points which are substantially a quarter of the circle from each other. The advantage of this is, steam is taken in to bear against the four

20 pistons at each revolution of the piston-wheel, whereby there is a more uniform pressure of steam in the case and an easier movement of the pistons than in other constructions known to the art, as the whole is hereinafter described

25 and shown.

30 *A* represents the periphery of the case, and *L* *L* are the heads thereof, of ordinary construction except the cam-grooves.

G is the piston-wheel, consisting of a hub, 40 piston-guide arms or plates *B B B B*, and a central shaft, *J*, which is driven by the piston-wheel in the ordinary manner to give motion to a drive-wheel, *K*. The periphery of the wheel *G* has formed therein an annular 45 groove whose radial section coincides with the radial sections of the cut-offs *E E*, which are made a portion of the inside of the cylinder *A*. The margins of the groove in the wheel *G* pass onto the sides or faces of the 50 cut-offs, whereby the grooved periphery with

the cut-offs form steam-tight bearings against the cylinder *A*. Packing *F*, however, may be employed to insure a perfect cut-off, if desired.

The pistons *C* are formed to have reciprocating movements in the guide-arms *B*, and to be projected to the inner surface of the cylinder *A*, and to be drawn in by the cam-groove by anti-friction attachments running in the groove, so as to pass the cut-offs *E*. As a matter of construction, the piston-wheel is formed 55 of an inner core, *M*, and an outer plate, *B*, bolted to each side thereof, in the ordinary manner of engine-work, and to relieve the valves *C* from unequal pressure steam-ports like the one shown at *I* may extend from the 60 annular groove in the wheel to their inner ends, and to attain proper bearings for the pistons they may run in grooves *N*, formed 65 radially in the plates *B*.

Both edges of the pistons *C* are provided 70 with ordinary anti-friction traveling guides or pivoted rollers *a*, running in a cam-groove, which is formed as follows: The channel is cut as deep as the rollers *a* are long and of a width corresponding to their diameter. The 75 lower portion of the cam from *P*' to *Q*' is a fourth of a circle, and that portion from *V* to *W* is the segment of and a quarter of a smaller circle than *P*' *Q*', and those portions from *Q*' to *W* on the right of the cam and from *P*' to 80 *V* on the left thereof are curves best calculated to ease the movements of the rollers *a* from the one segment to the other. This construction divides the cylinder *A* in four quarters, one quarter from *P* to *Q*, and the two others 85 between *P* and the cut-off *E* on that side of the cam, and between *Q* and the cut-off *E* on the other side of the cam, the last quarter being the cut-off portion of the case from *E* to *E*.

b shows the slots which allow the pivots *c* 90 to the rollers *a* to move radially.

Dotted lines *h*, Fig. I, show the throw of the pistons *C* in moving from the inner surfaces of the cut-offs to the cylinder *A*. The steam-ports are shown to pass into the case at the 95 right and left of the cut-offs *E E*, and they may pass through the heads *L* or the cylinder *A*, and either one may take or exhaust steam, as may be required for the direction the piston-wheel is to run.

Having thus described our invention, what we claim as new, and desire to secure by Letters Patent, is—

In rotary steam-engines having an exterior case composed of a cylinder, A, and heads L, the piston-wheel B G, with its reciprocating pistons, in combination, the cams in the heads, which are formed each on a small and large segment of a circle, and the interspaces

formed on curved lines to serve as a continuous guide for the rollers a, and the cut-offs E, placed inside of the steam-ports m m, as specified.

THOMAS SHIVERICK.
LEANDER J. WYNN.
